FIG.2

FIG.4

FIG.5

FIG.6

FIG.7

FIG.9

FIG.8

FIG.10

FIG.11

FIG.12

FIG.13

FIG.15

FIG.14

FIG.16

FIG.17

FIG.18

FIGURE 1 is a front elevation of a hearing aid showing my new design;

FIGURE 2 is a rear elevational view of the hearing aid illustrated in FIG. 1;

FIGURE 3 is a right side elevational view of the hearing aid illustrated in FIG. 1;

FIGURE 4 is a left side elevational view of the hearing aid illustrated in FIG. 1;

FIGURE 5 is a top plan view of the hearing aid illustrated in FIG. 1;

FIGURE 6 is a bottom plan view of the hearing aid illustrated in FIG. 1;

FIG. 7 is a front elevation of a second modified embodiment of the hearing aid illustrated in FIG. 1;

FIGURE 8 is a rear elevational view of the hearing aid illustrated in FIG. 7;

FIGURE 9 is a right side elevational view of the hearing aid illustrated in FIG. 7;

FIGURE 10 is a left side elevational view of the hearing aid illustrated in FIG. 7;

FIGURE 11 is a top plan view of the hearing aid illustrated in FIG. 7;

FIGURE 12 is a bottom plan view of the hearing aid illustrated in FIG. 7;

FIG. 13 is a front elevation of a third modified embodiment of the hearing aid illustrated in FIG. 1;

FIGURE 14 is a rear elevational view of the hearing aid illustrated in FIG. 13;

FIGURE 15 is a right side elevational view of the hearing aid illustrated in FIG. 13;

FIGURE 16 is a left side elevational view of the hearing aid illustrated in FIG. 13;

FIGURE 17 is a top plan view of the hearing aid illustrated in FIG. 13; and

FIGURE 18 is a bottom plan view of the hearing aid illustrated in FIG. 13.

The dominant features of my design reside in the full line portions.

I claim:

The ornamental designs for hearing aid, as shown and described.
